UNITED STATES PATENT OFFICE.

JOHN LEONARD GRIFFIN, OF BOSTON, MASSACHUSETTS.

SHIPPING-CRATE.

SPECIFICATION forming part of Letters Patent No. 651,011, dated June 5, 1900.

Application filed August 22, 1899. Serial No. 728,095. (No model.)

To all whom it may concern:

Be it known that I, JOHN LEONARD GRIFFIN, a citizen of the United States, residing at Boston, in the county of Suffolk and State 5 of Massachusetts, have invented a new and useful Shipping-Crate, of which the following is a specification.

This invention relates to shipping-crates in general, and more particularly to that 10 class designed for shipping lobsters; and it has for its object to provide means for the shipment of lobsters in which they may be kept alive for a longer period than is usual, in which the lobster may be maintained in a 15 fresh condition, and in which also a supply of cool salt water may be contributed to the lobsters in sufficient quantities to maintain them in a healthy condition.

In the drawings forming a portion of this 20 specification, and in which similar numerals of reference designate corresponding parts in the several views, Figure 1 is a perspective view showing the parts of the crate disassembled. Fig. 2 is a vertical longitudinal 25 section of the crate, showing the parts thereof in their proper position and also showing the arrangement of a lobster and of the ice and salt. Fig. 3 is a perspective view showing a lobster-claw and means for preventing 30 opening of the claw. Fig. 4 is a detail perspective showing the protecting burlap upon the head of the lobster.

Referring now to the drawings, 5 represents a rectangular case having a cover hinged thereto and provided at its upper edge with a strip 7, of felt or other material, and upon which the cover is adapted to rest and form an air-tight joint. Upon the inner surfaces of the sides and ends of the case are disposed 35 vertical strips 8, arranged in pairs, and the elements of each pair being opposite. Within the case and at the bottom and of a size to fit snugly against the strips 8 is a tray 10, having a foraminous bottom 11^a, of basket-work or other material, and which tray is divided into a plurality of compartments 11 through the medium of transverse partitions 12, and midway of the height of each compartment and at the ends thereof are arranged 45 strips 13, adapted to receive supplemental trays 14, of basket-work or other similar material, and which divide the compartments 11 into upper and lower divisions, as shown. Each of the supplemental trays 14 is pro-

vided with a handle 15, through the medium 55 of which it may be readily placed or moved with respect to the strips 13.

Upon the tray 10 is placed a similar tray 17, and any number of trays may thus be placed one upon the other. Above the uppermost 60 tray just described, and which in the present instance is the tray 17, is arranged a different style of tray 18, comprising end and side sills 19 and 20, and having a double bottom consisting of two layers of wire-netting 20' and 65 21, fixed to the end and side sills adjacent their lower edges, and which tray is separated into compartments by means of transverse partitions 22, the upper layer of netting 20' being in short sections reaching from one 70 partition to the next and reaching also from the end partitions to the adjacent end sills.

In the bottom of the case is formed a suitable number of ventilating-openings 25 to admit a suitable quantity of air to the crate 75 or easing, and it will of course be understood that the number and sizes of these openings may be varied as desired.

The tray 18 is supported from the upper edge of the easing 5 through the medium of 80 outwardly-directed clips 26, fixed upon the outer faces of the side sills, and which clips are the ends of metallic straps or bands passed transversely of the under side of the tray and then upwardly against the outer faces of the 85 side sills and having their extremities turned in opposite directions.

In making shipments with a crate of this style a section of burlap 28 is placed upon the floor of each division of each compartment 90 of the trays below the tray 18, and upon this burlap is placed a lobster, as shown in Fig. 2 of the drawings. A second piece of burlap 29 is then placed over the lobster, and the trays are then arranged properly within the 95 easing, each compartment containing a lobster having a section of burlap above and below it. Intermediate the wire-netting forming the bottoms of the tray 18 are disposed two sections of burlap 29' and 30, having a 100 quantity of rock salt 31 arranged between them, and upon the uppermost bottom is disposed ice, either in small pieces or in a solid cake for each compartment, as may be preferred. The tray 18 having been placed with 105 in the easing, the cover 6 is closed down and securely fastened and the crate is ready for shipment. With this arrangement it will be

seen that there is a slight circulation of air through and around the trays, while the air admitted is of such a small quantity as not to hasten the melting of the ice; also, that as 5 the ice gradually melts the water therefrom will pass downwardly upon the burlap covering of the salt and will then engage the salt and take up a portion thereof and will then drip to the burlap covering of the lobster next 10 below. The saturation of the covering of the lobster with the cool salt water will act to maintain the lobster in a healthy condition, and thus to prolong its life. From the uppermost lobsters or from the burlap covering 15 thereof the water will drip to the covering of the lobster next below, and so on downwardly and throughout the several trays. After passing through the entire tier of trays the water passes out of the openings 25.

20 As shown in Fig. 1 of the drawings, the tray 18 is kept spaced a suitable distance from the sides of the casing through the medium of blocks 31^a, fixed to the outer faces of the sides thereof.

25 From the foregoing description it will be seen that instead of subjecting the lobsters to direct contact with the ice and to fresh water the water from the ice reaches the salt in a comparatively-warm state, and thus when 30 it falls upon the lobsters does not injure them, and at the same time the location of the salt prevents melting of the ice.

While it is preferred to place a single lobster in each compartment, it may at times be 35 desired to thus arrange more than one, in which event, in order to prevent injury of one to another, it is preferred to place an elastic strap 35 around the claws thereof in substitution of the usual and cruel method which 40 consists in driving a peg through the joint of the claw.

In order to protect the claws of the lobsters 45 against injury, burlap is wrapped about them, as shown in Fig. 3 of the drawings, and a similar protection, as shown in Fig. 4, may be placed over the head and fastened down with a rubber band or with cord or wire. Also, as will be readily understood, a cord or wire may be substituted for the band which 50 holds the claw closed. As a further means for preventing injury of one lobster to another a cork 40 is placed upon the horn of the lobster. When this cork is employed, together with the wrapping of burlap or other 55 material, the lobsters may be packed one upon another in the crate without danger of injury to each other.

In the manufacture of a crate in accordance 60 with this invention any desired number of trays may be incorporated, and these trays may contain any number of compartments and divisions in accordance with the size of the crate and other conditions. Also the specific construction shown may be varied 65 and any suitable materials may be employed for the different parts without departing from the spirit of the invention.

Having thus described the invention, what is claimed is—

1. A shipping-crate, comprising a casing, 70 a plurality of trays within the casing having foraminous portions, and an ice-tray above the first-named trays adapted to receive ice and having a foraminous bottom for the passage of melted ice upon the trays therebelow. 75

2. A shipping-crate, comprising a casing having an air-tight cover and provided with an opening in its bottom, a plurality of trays within the casing and having foraminous bottoms, a tray supported above the first-named 80 trays and adapted to receive ice, and a double foraminous bottom for the uppermost tray adapted to receive salt between the elements thereof.

3. A crate, comprising a casing, a plurality 85 of trays within the casing and separated from the sides thereof by air-spaces, an air-inlet, a cover adapted to fit air-tight upon the casing, and an ice-tray suspended from the top of the casing, said ice-tray having a double 90 foraminous bottom and interposed absorbent material adapted to receive salt.

4. A shipping-crate, comprising a casing having vertical strips upon its inner faces, a plurality of trays each divided into compartments having foraminous bottoms, absorptive material within each compartment adapted to receive and cover a body to be preserved, and an ice-tray above the first-named trays and adapted to deliver the water from the 100 ice to the absorbent material.

5. A crate, comprising a casing, a plurality of trays within the casing, each comprising compartments and divisions having foraminous bottoms, absorbent material in each division adapted to receive a body to be preserved, an ice-tray suspended above the first-named trays and comprising compartments having double foraminous bottoms, absorbent material disposed between the elements of 105 each bottom, salt arranged within the absorbent material, and ice disposed upon the uppermost bottom.

6. A crate, comprising a casing having an air-tight cover and provided with an opening 115 in its bottom, a plurality of trays within the casing, each having a number of divisions having foraminous bottoms, a tray supported above the first-named trays and having a double foraminous bottom, said bottoms being adapted to receive salt between them, and the uppermost bottom being adapted to support ice, and absorbent material within each of the divisions of the first-named trays adapted 120 to cover a body to be preserved and to receive the melted ice from the ice-tray.

In testimony that I claim the foregoing as my own I have hereto affixed my signature in the presence of two witnesses.

JOHN LEONARD GRIFFIN.
